UNITED STATES PATENT OFFICE.

EDWIN J. REICH, OF BROOKLYN, AND GEORGE J. ELTZ, JR., OF NEW YORK, N. Y.,
ASSIGNORS TO MANHATTAN ELECTRICAL SUPPLY COMPANY, INC., OF NEW YORK,
N. Y., A CORPORATION OF MASSACHUSETTS.

LOUD SPEAKER.

Application filed November 26, 1923. Serial No. 676,918.

To all whom it may concern:

Be it known that we, EDWIN J. REICH, residing at Brooklyn, New York, in the county of Kings and State of New York, 5 United States of America, and GEORGE J. ELTZ, Jr., residing at 96 Wadsworth Terrace, New York city, New York, having invented certain new and useful Improvements in Loud Speakers, do hereby declare that the following is a full, clear, and exact description of the same.

This invention relates to new and useful improvements in telephonic receiving elements, and more particularly to improvements in telephone loud speakers.

It is the object of this invention to provide a telephone loud speaker which is simple in construction and operation, and which may be readily adjusted to vary the tone 20 output.

With this object in view, the magnet structure is mounted on a relatively heavy base the inertia of which will tend to maintain the magnets in their adjusted position. 25 According to another feature of the invention, a leaf spring formed into substantially a circle is placed under tension in response to all relative displacements of said diaphragm and magnet structure and this 30 serves to aid in maintaining the spacing between the two.

These and other features of the invention will more clearly appear from the following detailed description of a preferred embodiment thereof and the appended claims.

The drawings illustrate a telephone loud speaker exemplifying the various features of the present invention. Fig. 1 is a side elevation with parts broken away; Fig. 2 is a 40 top plan view; Fig. 3 is a cross section of the receiving element proper contained in the loud speaker; Fig. 4 is a bottom plan view of the receiving element; and Fig. 5 is a perspective view of a spring by means 45 of which the receiving element is held in its adjusted position.

Referring now to the drawings, 1 is a cup provided with a solid and relatively heavy base 2 and arranged to enclose the 50 telephonic receiving element. The open end of the cup is closed by a top 3 held in position by means of bolts such as 4 projecting through the base 2 and engaging with their screw-threaded ends internally screw

threaded apertures 5 provided in the top 3. 55 The top 3 is centrally perforated at 6, said perforation being surrounded by a collar 7 forming a unitary structure with the top 3. An amplifying horn (not shown) may be fitted over this collar 7. 60

The lower face of the top 3 is recessed in a manner to form a shoulder 8 and an internally screw threaded rim 9. The internally screw threaded rim 9 cooperates with the externally screw threaded end of a cylindrical casing 10 which contains the magnet structure of the receiver. A thin steel diaphragm 11 is firmly clamped against the shoulder 8 by the cylindrical casing 10. The central part of the cylindrical casing 70 10 is provided with a horizontal strengthening rib 12, the casing 10 being further strengthened due to the provision of outwardly projecting vertical ribs 30. The lower part of casing 10 is internally screw 75 threaded to cooperate with an external screw thread provided on a disc 13. The magnet coils 14 and the horse-shoe 15 by means of which the magnetic circuit is completed, are mounted on the disc 13 by means 80 of bolts 16 traversing perforations in said disc and having screw threaded ends cooperating with nuts 17. The horse-shoes 15 and the magnet coils 14 are spaced from the upper face of the disc 13 by means of a 85 suitably shaped washer 18. The disc 13 is perforated at two other points where two binding posts 19 and 20 project through it, said binding posts being properly insulated from each other and from the disc 13 by 90 means of insulation 21. The terminal wires of the coils 14 are connected to the ends of these binding posts 19 and 20 projecting through the upper face of the disc 13 (not shown). 95

Small perforations or indentations 22 provided in a centrally located raised portion of disc 13 are adapted to receive lugs 23 projecting from a lever 24 which may be held against the disc 13 by means of a screw 100 25. The lever 24 may be adjusted into any position with the lugs 23 engaging two opposite holes 22 and then maintained in such position by tightening the screw 25. When the lever 24 is thus firmly held in position 105 then, by means of it, the disc 13 may be rotated in a clockwise or a counterclockwise direction. When the disc is thus rotated in

a clockwise direction, then the pole pieces of the magnet 14 are caused to approach the diaphragm 11 and when rotated in a counterclockwise direction the magnet structure is caused to move away from the diaphragm. The end of the lever 24 projects through a slit 26 provided in the cup 1 and may thus be readily handled by the operator who may thus control the modulating without interfering with the location of or connections to the loud speaker.

In order to hold the magnet structure in its adjusted position a leaf spring 27, which as clearly shown in Fig. 5 is bent into a shape that has three raised and three lowered portions, is provided between the cylindrical casing 10 and the disc 13. The three lowered points engage the shoulder formed by the rib 12 and the three raised points engage the disc 13 around its periphery. The spring 27 is split at 28 to permit a relatively wide play. After the disc 13 is screwed into place and the spring 27 placed under tension, such spring will remain under tension while the disc is rotated back and forth within desired margins and thus the magnet structure will be held through the agency of this spring in whichever position it is desired.

In addition to the spring 27, the magnet structure is maintained in its adjusted position due to the fact that the disc 13 is of relatively heavy material and its inertia will have therefore a tendency to prevent vertical displacements of the magnet structure. The provision of spring 27 and the weight of disc 13 avoids the necessity of providing special means for locking the magnet structure in its adjusted position. Not only is the provision of such special holding and locking means done away with, but also the screw thread by means of which the disc 13 is held in the cylindrical casing 10 may be very coarse, whereby the cost of manufacturing and assembling is materially reduced and a relatively slight movement of the lever 24 will result in a relatively large vertical displacement of the magnet structure 14 with respect to the diaphragm 11, permitting thus readily to modulate the tone output.

What we claim is:

1. In a telephone loud speaker, a casing, a diaphragm, means for clamping the edge of said diaphragm against the upper end of said casing, a disc screw-threaded around its periphery and cooperating with the in-

ternally screw-threaded lower end of said casing, a magnet structure carried by said disc, an internal projection on said casing near its lower end, and a spring placed under tension between said projection and said disc.

2. In a telephone loud speaker, a cup, a top therefor, a casing fastened to said top, a diaphragm held between said top and the upper end of said casing, a disc screw-threaded around its periphery and cooperating with the internally screw-threaded lower end of said casing, a magnet structure mounted on said disc, and a substantially circular spring exerting uniform pressure on said casing and disc near their peripheries.

3. In a loud speaker, a cup, a top therefor, a diaphragm seated in an inner recessed portion of said top, a casing attached to said top, a relatively heavy disc provided with a relatively coarse external screw thread cooperating with said casing, a magnet structure mounted on said disc, a split leaf spring having a plurality of raised and lowered portions engaging said casing and said disc near their peripheries when the disc is screwed into place, a lever fastened to said disc, and a slot in said cup through which the free end of said lever projects.

4. In a loud speaker, a cup having a relatively heavy base and a top, an aperture in said top, a collar projecting from said top and surrounding said aperture, a metallic diaphragm seated in an inner recessed portion of said top, a casing having an externally screw threaded upper end adapted to engage an internal screw thread in said recessed portion to clamp said diaphragm in place, an inwardly projecting horizontal rib in said casing, a relatively heavy disc provided with a relatively coarse external screw thread, a magnet structure mounted on said disc, a relatively coarse inner screw thread on the lower portion of said casing cooperating with the external screw thread on said disc, a split leaf spring having a plurality of raised and lowered portions engaging one face of said rib and said disc around its periphery when the disc is screwed into place, a lever fastened to said disc, and a slot in said cup through which the free end of said lever projects.

In witness whereof, we hereunto subscribe our names this 21st day of November, 1923.

GEORGE J. ELTZ, Jr.
EDWIN J. REICH.
